UNITED STATES PATENT OFFICE.

CHARLES BOOZE, OF BUFFALO, NEW YORK, ASSIGNOR TO M. H. BIRGE & SONS,
OF SAME PLACE.

DESIGN FOR WALL-PAPER.

SPECIFICATION forming part of Design No. 20,325, dated November 18, 1890.

Application filed September 27, 1890. Serial No. 366,382. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification, reference being had to the accompanying photograph, forming part thereof.

10 The leading feature of my design consists of sprays of leaves and flowers of the daisy arranged irregularly over the surface of the paper, as represented in the accompanying photograph. The stems and vines of the leaves and flowers are disconnected and ar-

ranged in loose groups extending upwardly over the paper with the leaves and flowers intertwining and drooping from the vines.

15 The design is printed upon tinted paper of any desired color.

What I claim is—

The design for wall-paper herein shown and described.

Witness my hand this 13th day of September, 1890.

CHARLES BOOZE.
